Primary Examiner — Robert M Spear*Assistant Examiner* — Marissa J Cash(74) *Attorney, Agent, or Firm* — Gardner Groff Greenwald & Villanueva, PC(57) **CLAIM**

The ornamental design for a syringe tip cap, substantially as shown and described.

DESCRIPTION

FIG. 1 is a first perspective view of a syringe tip cap according to another embodiment of the design.

FIG. 2 is a second perspective view of the syringe tip cap of FIG. 1.

FIG. 3 is a bottom view of the syringe tip cap of FIG. 1.

FIG. 4 is a top view of the syringe tip cap of FIG. 1.

FIG. 5 is a first side view of the syringe tip cap of FIG. 1.

FIG. 6 is a second side view of the syringe tip cap of FIG. 1.

FIG. 7 is a first end view of the syringe tip cap of FIG. 1; and, FIG. 8 is a second end view of the syringe tip cap of FIG. 1. In the drawings, the broken lines depict environmental subject matter only and form no part of the claimed design.

1 Claim, 6 Drawing Sheets---
